[57] **ABSTRACT**

Novel halophenoxy-s-triazine derivatives and salts

thereof characterized by improved solubilities having the formula:-

wherein X represents from one to five halogen atoms and R1 is either of

wherein R2 is alkyl having one to five carbon atoms, halogenated alkyl having one to five carbon atoms, alkali metal or ammonium, R3 is hydrogen, alkyl having two to 18 carbon atoms, halogenated alkyl having two to 18 carbon atoms or cycloalkyl, and R4 is alkyl, cycloalkyl, aryl, halogenated alkyl, halogenated cycloalkyl or halogenated aryl, and wherein R3 and R4 taken together with the nitrogen atom to which they are attached form a heterocyclic ring.

The novel triazine derivatives and their salts are suitable for use as water repellants, parting agents, textile adjuvants, as fire retardants, fungicidal, phytotoxic, bactericidal and insecticidal agents.

**HALOGENPHENOXY-S-TRIAZINE DERIVATIVES
HAVING IMPROVED SOLUBILITY**

This invention relates to halogenphenoxy-s-triazine derivatives having improved solubility characteristics.

According to the present invention there is provided a novel group of halogenphenoxy-s-triazine derivatives which have the formula:-

wherein X represents from one to five halogen atoms and R₁ represents a phosphonic acid radical of the formula:-

or an amino group of the formula:-

in which R₂ represents alkyl, halogenated alkyl, alkali metal, or ammonium, R₃ represents hydrogen, alkyl containing two to 18 carbon atoms, halogenated alkyl containing two to 18 carbon atoms or cycloalkyl and R₄ represents alkyl, containing two to 18 carbon atoms, halogenated alkyl containing two to 18 carbon atoms, cycloalkyl or aryl and wherein R₃ and R₄ taken together can form a heterocyclic ring.

The novel derivatives of the invention are characterized in that they are soluble in organic solvents. The highly chlorinated halogenphenoxy-s-triazines which have heretofore been available and particularly those containing the pentachlorophenoxy group, exhibit only a very slight solubility in organic solvents.

In accordance with the invention it has been found that the solubility in organic solvents is considerably improved by replacing the halogen atoms in carbon-halogenated halogenphenoxy-s-triazines, i.e., those which still contain reactive halogen atoms, with the above-defined moiety R₁. Thus for example, 2-chloro-4,6-di-(pentachlorophenoxy)-s-triazine, which has a melting point of 327° C is substantially insoluble in nearly all organic solvents, while 2-phosphonic acid diethylester-4,6-di-(pentachlorophenoxy)-s-triazine is readily soluble in aromatic and chlorinated hydrocarbons. This can be seen from the following Table. The compatibility of the triazine compounds with aromatic solvents is of great importance in practice.

Comparison of solubility in various organic solvents at 25°C of compounds a and b in grams per 100 milliliters.

	a) 2-phosphonic acid di-ethylester-4,6-di-pentachlorophenoxy-s-triazine	b) 2-chloro-4,6-di-pentachlorophenoxy-s-triazine
xylene	10%	1%
o-dichloroethane	10%	1%
o-dichlorobenzene	10%	5-6% at 120°C 1% at 25°C
chloroform	9%	1%
acetone	8%	1%
ethanol	5%	1%

Where, in the above set out formula R₁ is

the preparation of the new triazine compounds is carried out by reacting a halogenphenoxy-s-triazine with a phosphorus acid ester at a temperature between 50° C. and 250° C and preferably at a temperature of from 80° C to 200° C. The re-esterification can be carried out both in the fused state and with an organic solvent. The reaction temperature is increased as the reaction proceeds so that the reaction mixture is constantly boiling. Alkyl halide is split off in the reaction, and the course of the reaction can be followed on the basis of the quantity of alkyl halide that is recovered. The reaction generally requires from 1 to 6 hours. After the evolution of alkyl halide has ended, the unreacted reactants are separated off by vacuum distillation. In most instances the distillation residue is analytically pure and requires no further purification measures.

Aliphatic and aromatic hydrocarbons as well as simple and cyclic ethers are suitable as solvents for use in the reaction. It is advantageous to use not only the solvents in pure form, as for example, an aliphatic hydrocarbon compound such as isooctane, but also their mixtures can be used, such as benzene fractions, instance fractions having a boiling range of from 120° to 200° C.

Chlorinated hydrocarbons such as dichlorothane, tetrachlorethylene, and pentachlorethane, can also be used as solvents. Benzene, toluene, o-dichlorobenzene and xylene are examples of suitable aromatic hydrocarbons. Instances of suitable ethers include: diisopropyl ether, diisoamyl ether, diphenyl ether, 1,4-dioxane etc. The above enumeration is indicative of the fact that both aliphatic and aromatic open-chain ethers can be satisfactorily used. Polar solvents such as dimethylsulfoxide, dimethylformamide, the dimethyl ether of diethylene glycol, and decaline, have also been found to be useful as solvents.

The starting materials for use in the process of the invention can be halogenated phenoxy-triazine derivatives containing reactive chlorine atoms, such as have been described in U.S. Pat. application Ser. No. 737129, now abandoned.

The phosphorus acid esters which can be used in the reaction with the triazine derivatives include the trialkyl phosphites in general. Lower alkyl esters of phosphorus acid, such as triethyl phosphite, tripropyl phosphite, etc., are preferred for the reaction. Halogenated trialkylphosphites, such as tris-(β -chlorethyl)-phosphite can also be advantageously used in the reaction according to the invention.

The saponification of these phosphonic acid ester derivatives with alkali to thereby form the alkali salts of phosphonic acid increases the solubility of the resulting compounds in water.

The saponification to form the salts is carried out by conventional methods, as for instance, by dissolving the phosphonic acid ester derivatives in organic solvents and heating them with an alkali.

The organic solvents which can be used for dissolving the phosphonic acid ester derivatives include alcohols and ketones, as for example ethanol, acetone etc., as well as the solvents mentioned heretofore in

connection with the reaction of the halogenphenoxy-s-triazines with alkyl phosphites.

The preparation of the compounds of the invention in which R_1 represents an amino radical, is carried out by reacting a C-chloride of a halogenated phenoxy-s-triazine, in the presence of a tertiary amine or of an acid amide as catalyst, at a temperature between 50° C and 250° C and preferably 80° C to 200° C, with an amine of the formula:

wherein R_3 and R_4 have the same significances as given above. The reaction can be conducted either with the reactants in the fused state or in an inert solvent. The inert solvent then having the function both of a genuine solvent and of a dispersing agent. The solvents which have been enumerated as suitable for use in the reaction of the halogenphenoxy-s-triazine with phosphorus acid esters can also be used for the reaction with the amine

The catalysts for use in the reaction are tertiary amines having aliphatic, cycloaliphatic and aromatic radicals in which case the substituted imines are to be understood as constituting a type of cyclic tertiary amine.

Other catalysts which may be used are acid amides or N-mono or di-substituted acid amides of monobasic, aliphatic, aromatic or araliphatic carboxylic acids having one to 18 carbon atoms. These acid amides have been described for instance in U.S. Pat. application Ser. No. 737,129, now abandoned.

To some extent, however, the amines used for the reaction themselves serve as reaction catalysts, so that the use of a special catalyst of the kind described above can in many instances be dispensed with.

The new compounds and their salts can be used as water repellants, parting agents, dressings for glass fabrics, textile adjuvants, for the surface treatment of various materials and articles because of their fire-retardant, fungicidal, phytotoxic, bactericidal and insecticidal properties. They can also be used as additives for varnishes and enamels.

The following Examples are given for the purpose of more clearly illustrating the invention and are not to be construed as limiting.

EXAMPLE 1

2-phosphonic acid diethylester,6-di-(trichlorophenoxy)-s-triazine

50.7 g of 2-chloro-4,6-di-(trichlorophenoxy)-s-triazine and 18.6 ml of triethylphosphite were weighed out and placed in a 250 ml 4-necked flask equipped with a stirrer, condenser, thermometer and a nitrogen gas introducing tube. The reaction mixture was slowly heated to 155° C and stirred for 2 hours at this temperature while being maintained under a current of nitrogen. The mixture was thereafter cooled to 120° C and the excess triethylphosphite removed by distillation in vacuo. The recovered product had a melting point of 74°-78° C.

EXAMPLE 2

2-phosphonic acid diethylester-4,6-di-(pentachlorophenoxy)-s-triazine

30 g of 2-chloro-4,6-di-(pentachlorophenoxy)-s-triazine were weighed out, under nitrogen gas, into a 250 ml 5-necked flask provided with stirrer, condenser, thermometer, nitrogen gas introduction tube and a dropping funnel. 50 ml of xylene were added thereto and then 8.95 ml of triethylphosphite were introduced drop by drop at 60° C. The reaction mixture was refluxed for 1 hour until no further ethyl chloride evolved. Following removal of the solvent by distillation, the concentrate was dried in vacuo. Yield 95%, M.P. 158° C.

	Analysis	Found	Calculated %
	C	31.67	30.60
	H	1.51	1.34
	N	5.83	5.63
20	Cl	47.10	47.55
	F	4.30	4.16

The sodium salt of this compound was prepared as follows: 8 grams of the substance were dissolved in 100 ml of acetone and then added under stirring to a sodium hydroxide solution in water (1 gram/5 ml H_2O). After 30 minutes stirring, the solution mixture was evaporated.

EXAMPLE 3

2-[phosphonic acid di-(β -chlorethyl)-ester]-4,6-di-(tetrachlorophenoxy)-s-triazine

There were introduced into a 100 ml 4-neck flask provided with stirrer, condenser, thermometer, and nitrogen gas introduction tube, 28.8 g of 2-chloro-4,6-di-(tetrachlorophenoxy)-s-triazine and 13.5 g of tris- β -chlorethylphosphite. While maintained under a current of nitrogen gas, the reaction mixture was slowly heated to 200° C and stirred at this temperature for 2 hours. The recovered product had a melting point of 111°-114° C.

	Analysis	Found	Calculated %
45	C	31.40	31.20
	H	1.35	1.37
	N	5.63	5.67
	Cl	48.46	48.60
	P	4.40	4.20

EXAMPLE 4

2-anilide,4,6di(2,4,6-trichlorophenoxy)-s-triazine

18.4 g of cyanuric chloride, 39.5 g of 2,4,6-trichlorophenol and 0.5 ml of dimethylcyclohexylamine were introduced into a three-necked flask provided with stirrer, condenser and introduction tube and 120 ml of xylene then added. The mixture was stirred at the boiling temperature of the xylene, and the HCl gas which evolved was flushed out of the reaction mixture with nitrogen gas and trapped in caustic soda solution. After approximately 66% HCl had been split off, 9.3 g of aniline were added to the reaction mixture. The reaction was completed after a period of about 29 hours. The precipitate which developed was filtered and dried. The melting point of the product was 186°-188° C.

EXAMPLE 5

2-anilide, 4,6-di-(pentachlorophenoxy)-s-triazine

In a three-necked flask provided with stirrer, condenser and introduction tube, 18.4 g of cyanuric chloride, 53.3 g of pentachlorophenol and 0.5 ml of quinoline were combined in 120 ml of xylene. The mixture was stirred at the boiling temperature of the xylene and the HCl gas which evolved was flushed out of the reaction mixture with N₂ and entrapped in NaOH solution. After 66% HCl had been split off, 9.3 g of aniline were added to the mixture. Following a period of about 19 hours, the reaction was completed. The precipitate which was developed was filtered off and dried. M.P. 271°-273°C.

EXAMPLE 6

2-anilide, 4,6-di-(tribromophenoxy)-s-triazine

In a three-necked flask provided with stirrer, condenser and introduction tube, 18.4 g of cyanuric chloride, 66.2 g of tribromophenol and 0.5 ml of quinoline were combined and then 120 ml of xylene were added thereto. The mixture was stirred at the boiling temperature of the xylene and the HCl gas which was

A product having a melting point of 207°-209°C was obtained.

EXAMPLE 9

5 2-di-(2-ethylhexylimino)-4,6-di-(pentachlorophenoxy)-s-triazine

The procedure of Example 5 were repeated and 19.34 g of 2-chloro-4,6-di-(pentachlorophenoxy)-s-triazine were reacted with 7.18 g of di-(2-ethylhexylimine) and xylene as solvent.

10 A product was obtained having a melting point of 107°-110°C.

EXAMPLE 10

15 2-octylimino-4,6-di-(2,4,6-tribromophenoxy)-s-triazine

Using a procedure analogous to that set out in Example 6, 22.25 g of 2-chloro-4,6-di-(2,4,6-tribromophenoxy)-s-triazine were reacted with 3.88 g of n-octylamine as catalyst and xylene as solvent.

20 A product having a melting point of 124°-128°C was obtained.

25 In like manner, the compounds listed in the Table which follows were prepared.

evolved was flushed out of the reaction mixture with N₂ and trapped in NaOH solution. After 66 percent of HCl had split off, 9.3 g of aniline were added to the reaction mixture. The reaction had ended after about 19 hours. The precipitate which had developed was filtered off and dried. The melting point of the recovered triazine was 220°-222°C.

EXAMPLE 7

2-(2-ethylhexylimino)-4,6-di-(2,3,4,6-tetrachlorophenoxy)-s-triazine

Using a procedure analogous to that set out in Example 3, 23.01 g of 2-chloro-4,6-di-(2,3,4,6-tetrachlorophenoxy)-s-triazine were reacted with 5.12 g of 2-ethyl-1-hexyl-amine in the presence of 0.5 ml of N,N-dibutylaniline as catalyst and xylene as solvent.

55 A product having a melting point of 114° to 116°C was thereby obtained.

EXAMPLE 8

2-butylimino-4,6-di-(2,4,6-tribromophenoxy)-s-triazine

By a procedure analogous to that of Example 4, 22.25 g of 2-chloro-4,6-di-(2,4,6-tribromophenoxy)-s-triazine were reacted with 2.2 g of n-butylamine and xylene as solvent.

I claim:

1. A member of the group consisting of compounds having the formula:

45 wherein X represents from one to five chlorine atoms, and R₁ represents a member selected from the group of

50 wherein R₂ represents a member of the group consisting of alkyl having one to five carbon atoms, halogenated alkyl having one to five carbon atoms, alkali metal and ammonium, R₃ is hydrogen or a two to 18 carbon atom member selected from the group consisting of alkyl, cycloalkyl and haloalkyl, and R₄ is a two to 18 carbon atom member selected from the group consisting of alkyl, cycloalkyl, haloalkyl and carbocyclic aryl, wherein R₃ and R₄ taken together are alkylene and taken together with the nitrogen atom to which they are attached can also form a cycloalkylimino ring having no more than six carbon atoms,

and alkali and ammonium salts thereof.

2. A compound according to claim 1 designated 2-phosphonic acid diethylester-4,6-di-(trichlorophenoxy)-triazine.

3. A compound according to claim 1 designated 2-[phosphonic acid di-(β -chlorethyl)-ester]-4,6-di-(tetrachlorophenoxy)-triazine.

4. A compound according to claim 1 designated 2-phosphonic acid diethylester-4,6-di-(pentachlorophenoxy)-triazine.

5. A compound according to claim 1 designated 2-anilide, 4,6-di(2,4,6-trichlorophenoxy)-s-triazine.

6. A compound according to claim 1 designated 2-anilide, 4,6-di-(pentachlorophenoxy)-s-triazine.

7. A compound according to claim 1 designated 2-anilide, 4,6-di-(tribromophenoxy)-s-triazine.

8. A compound according to claim 1 designated 2-(2-ethylhexylimino)-4,6-di-(2,3,4,6-tetrachlorophenoxy)-s-triazine.

9. A compound according to claim 1 designated 2-butylimino-4,6-di-(2,4,6-tribromophenoxy)-s-triazine.

10. A compound according to claim 1 designated 2-di-(2-ethylhexylimino)-4,6-di-(pentachlorophenoxy)-s-triazine.
